FLEXIBLE UNDERLIE FOR RUGS

Ferd W. Bingell, Cleveland, Ohio

Application March 15, 1950, Serial No. 149,790

4 Claims. (Cl. 117—8)

1

This invention relates to an underlie for rugs and other floor coverings and particularly to a non-skid underlie which is flexible flatwise so as to conform to the general plane and contour of the floor and is operative to grip highly polished floors or other supporting surfaces frictionally so as to retain its position thereon and to engage the underside of a rug so as to retain the rug in fixed position in the plane of, and relative to, the underlie.

The invention also relates to a method of making an underlie such as above described.

The underlie comprises essentially coarse open mesh metal fabric composed of strands of flexible wire which are of relatively small diameter, or of narrow strips of metal which are relatively thin, so that it is flexible flatwise, the strands of the fabric being coated with soft resilient rubber or rubber composition, with the composition spanning and closing the mesh and protruding from the fabric at the underside in the form of multitudinous small soft resilient protuberances which are aligned with the meshes, respectively, and of which base portions in the plane of the fabric are constrained by the strands from expansion laterally in said plane, the protuberances being spaced apart from each other so as to engage a floor or supporting surface and frictionally constrain the underlie from movement therealong, and the underlie having means exposed on its upper surface which are operative to engage the undersurface of the rug and constrain it from movement relative to the underlie.

The method of making the underlie comprises essentially applying on the open mesh metal fabric a coating of rubber or rubber composition in plastic condition which sets in soft and resilient condition and while the rubber or composition is in plastic condition applying pressure to the composition from one face of the fabric to cause the composition to embed the fabric and to cause the part of it which bridges the openings in the fabric to bulge and protrude outwardly from the face of the fabric in the form of multitudinous protuberances respective to and aligned with the openings and forming a roughened surface on the opposite face of the fabric by the configuration of the rubber or composition or the bonding thereto of irregular particles or granules of material.

Heretofore, underlies have been provided in the form of a sheet of rubber or rubber composition having a plurality of bulges distributed over the undersurface and with a network of integral ribs interconnecting the adjacent bulges, the op-

2

posite face of the underlie having concavities corresponding to the bulges or protuberances and to the ribs, respectively. Such mats while reducing slippage of the supported rug have a tendency to creep along the supporting floor and to creep relative to the rug, apparently due to the elastic deformation and expansion and recovery of the underlie along its plane, this deformation being distributed and transmitted over a substantial area of the underlie surrounding the point of application of pressure. For example, pressure applied normal to the underlie causes vertical compression of the bulges or pads with consequent lateral expansion thereof. The resiliency of the composition does not completely absorb the resultant lateral components of movement. Since the bulges or protuberances adjacent to those under vertical compression are resting on the floor only under the limited weight of the rug and their own weight and are not gripping the floor firmly, they are moved slightly outwardly from the area of applied pressure. Upon removal of the pressure those protuberances originally compressed no longer firmly grip the floor so that when they contract toward original condition, they can do so as readily by moving themselves slightly toward the adjacent bulges or protuberances as by drawing the adjacent protuberances back toward themselves. Thus with each application of pressure there is a small increment of movement or shift of the underlie along the floor surface. This is increased to some extent by the manner of application of pressure applied by the foot of one walking on the floor. Such pressure, due to rocking of the foot of the wearer from the heel to the ball of the foot or about the ball of the foot causes the point of application of pressure to travel along the plane of the underlie much as though a roller were rolled across the rug. Thus a bulge adjacent the instantaneous point of pressure application is moved slightly by lateral expansion of the bulges or protuberances under pressure and while so moved is itself placed under pressure in its changed position and thus grips the floor tightly as the pressure on the original protuberance is released. Consequently the released bulge in restoring itself draws itself toward the now compressed adjacent bulge which is firmly held against the floor by the pressure. These minute increments of movement cause gradual creepage of the underlie.

In accordance with the present invention, each of the protuberances of the underlie is individually confined at its base portion in the plane of

the underlie by non-elastic strands of metal so that any lateral expansion of the base portion of a given protuberance under downwardly directed pressure is prevented, the resultant forces normally tending to cause such expansion being balanced by reactant forces of the wire strands instead of being distributed and transmitted to adjacent areas of the underlie. Consequently there is no initial displacement or movement in the plane of the underlie of the bulges adjacent to the pressure area and consequently no permanent increment or displacement of travel of the underlie. Instead, each protuberance acts as a self-contained and independent unit so far as elastic deformation is concerned, yet the base portions of the multitudinous units are secured in fixed position relative to each other in the plane of the underlie. Furthermore, the protuberances preferably are of large projected area in the plane of the underlie relative to their greatest dimension normal to such plane, thus making them operable to flatten and engage a large area of the floor with a minimum of resultant expansive force in the plane of their bases. The wire fabric bonded with rubber composition develops a very high degree of rigidity in its plane. Likewise the proportions of the protuberances greatly reduce any tendency of them to roll about their points of contact with the floor under a force having a component normal to the floor and one parallel to the floor. If the protuberances are of a height which is large relative to their projected area in the plane of the underlie, these would have a much smaller area bearing against the floor in relation to their height and would tend to rock about the contact area, due not only to the parallel component of the force but overbalance of the normal vertical component. Thus their bases in the plane of the underlie would tend to travel appreciably parallel to the floor. Preferably, therefore, the protuberances of the present underlie are of large projected area relative to their height. For example, if the projected area is round it may have a diameter of about three to five times the overall thickness of the underlie. The overall thickness of the underlie should be kept as small as possible having due regard to strength and to the amount of padding desired beneath the particular rug. An underlie having an overall thickness of about $\frac{1}{8}$ inch to $\frac{3}{8}$ inch and preferably about $\frac{1}{4}$ inch is preferred for most conditions.

The objects and other advantages of the present invention will become apparent from the following description wherein reference is made to the drawings, in which:

Fig. 1 is a top plan view of a fragment of an underlie embodying the principles of the present invention, portions thereof being cut away for clearness in illustration;

Fig. 2 is a cross sectional view taken on the line 2—2 of Fig. 1;

Fig. 3 is a bottom plan view of the underlie illustrated in Figs. 1 and 2;

Fig. 4 is an end elevation of the underlie in operating position between the rug and floor, the floor being shown in section;

Fig. 5 is a top plan view similar to Fig. 1 illustrating a modification of the underlie of Fig. 1;

Fig. 6 is a cross sectional view taken on the line 6—6 of Fig. 5;

Fig. 7 is a top plan view similar to Fig. 1 illustrating another modification of the underlie, part thereof being cut away for clearness in illustration;

Fig. 8 is a cross sectional view taken on the line 8—8 in Fig. 7;

Fig. 9 is a fragmentary enlarged sectional view taken on the right hand offset portion of the line 8—8 in Fig. 7 and corresponding to the right hand portion of the underlie shown in Fig. 8;

Fig. 10 is a top plan view of a fragment of an underlie similar to Fig. 1 but with a metal fabric of flat strands instead of round wire strands, illustrated in Fig. 1; and

Fig. 11 is a right end view of the metal fabric of the underlie illustrated in Fig. 10.

Referring to the Figs. 1 through 3 inclusive, the underlie there illustrated comprises a coarse open mesh fabric 1 of metal, such as woven wire or offset metal which is relatively stiff in its plane but readily flexible flatwise. The metal fabric 1 is embedded in and bonded to a matrix, indicated generally at 2, which preferably is of soft resilient rubber, either real or synthetic, or to a composition of one or both. The term "rubber" as used throughout the description and claims is meant to include any one or a mixture of the above materials of the matrix inasmuch as the physical characteristics rather than the chemical characteristics are controlling. The matrix 2 is shown as being comprised of two layers, 3 and 4, respectively, integrally bonded together and to the metal fabric so as to provide a unitary structure, the particular construction shown resulting from the method used in manufacture thereof.

The metal fabric, as stated, is preferably open and preferably of relatively coarse mesh yet is sufficiently flexible so that the resulting underlie can conform readily to the variations in supporting surface or floor. The strands of the metal fabric are relatively thinly coated with the matrix and the matrix spans and closes the openings of the fabric. At the underside the matrix is in the form of multitudinous well-defined protuberances which are aligned with the openings of the fabric respectively, and are spaced apart from each other laterally. Each protuberance is generally in the form of a spherical sector on its undersurface, thus presenting a rounded or globular convex surface downwardly. The base portion of each protuberance, which portion is that lying between the planes of the metal fabric, is confined and restrained from lateral expansion in the plane of the fabric. Thus to a great degree the individual protuberances are isolated from each other so far as lateral elastic deformation is concerned. As a result lateral expansion of one protuberance does not transmit any bodily movement to those adjacent thereto. The protuberances 5 are large in horizontal projection relative to their height or dimension normal to the plane of the underlie. The upper surface of the underlie formed by the top layer 4 is also of soft resilient rubber and as mentioned is integrally bonded to the upper surface of the lower layer to form the matrix.

On the exposed upper surface of the top layer 4 are roughening means for engagement with the rug to anchor the rug against relative movement in the plane of the underlie.

In the form illustrated in Figs. 1 through 3 the anchor means comprises relatively coarse irregular particles or granules 6 of material, such as ground cork, ground or shredded rubber or rubber and fiber composition, and the like. These particles may be resilient to some degree so as not to cut or damage the rug but usually are much less resilient than the matrix. These are bonded or cemented to the matrix, depending

upon the manner of manufacture, and are evenly distributed over the upper surface and present a multitude of peaks or projections with valleys therebetween so as to better engage and hold the rug.

The underlie illustrated in Figs. 1 through 3 is shown in Fig. 4 in operating position on a floor F supporting a rug R.

If desired, the upper layer 4 may be omitted and the particles applied directly on the upper surface of the layer 3.

Such a modification is shown in Figs. 5 and 6 in which the irregularities normally occurring in the upper surface, due to the cross strands and open mesh of the fabric, assist in restraining the rug from sliding and creeping on the underlie.

Referring specifically to Figs. 5 and 6, the open mesh metal fabric is indicated at 7 and is coated by matrix 8, the coating of the individual strands being relatively thin and the fabric lying near the upper surface of the matrix. The lower face of the matrix is in the form of a multitude of protuberances 9 similar in form and operation to the protuberances 5. Irregular coarse particles 10 of materials are distributed over the upper surface of the matrix and bonded thereto. The main difference in the two forms described is in their thickness and result largely from their respective methods of manufacture. In the form illustrated in Figs. 1 through 4 the fabric 1 is spread horizontally and a layer of the rubber in viscous condition, as a result of plasticizing by heat or by a volatile solvent or plasticizer, is spread approximately uniformly over the upper surface. Next a sheet of rubber is laid over the viscous rubber layer and pressed evenly downwardly thereagainst, thus forcing the viscous rubber through the mesh of the fabric and around the individual strands, thoroughly coating the latter. The pressure is continued until the desired portion of the viscous rubber has passed through the mesh and formed protuberances of the desired height at the underface, these protuberances automatically taking the spherical shape heretofore described. This also bonds the upper layer or sheet 4 to the layer 3 of viscous rubber and the underlie becomes a unitary structure with the fabric well embedded therein and bonded thereto. The top of the layer 4 is then sprinkled with the particles or granules of material and these are lightly pressed thereagainst so as to make them adhere or to partly embed them while leaving a number of irregularities exposed above the normal plane of the layer 4. The sheet or layer 4 might be of somewhat plasticized rubber in which case the particles can be bonded thereto before setting. If, however, the sheet or layer 3 is already set, a coat of cement may first be applied for bonding the particles thereto. Likewise, if desired, the wire fabric, before placing the layer 3 of viscous rubber thereon, may be lightly coated by brushing it with a small quantity of the same or like material, thus assuring that all strands of the metal fabric will be coated and bonded to the final underlie.

The pressure may be applied to the upper surface by means of a roller or platen, the roller or platen preferably being steam heated and of the usual type having a porous surface through which steam and moisture can escape against the surface of the material to prevent sticking of the rubber to the platen or roller. The latter type of platen or roller is particularly desirable in producing the underlie of Figs. 5 and 6 due to the

tackiness of the viscous rubber which is directly exposed to the platen or roller.

Air pressure also may be applied to the upper face for forming the protuberances but in such case care must be exercised to assure that the viscous rubber is of uniform consistency and will flow evenly.

Referring next to Figs. 7 through 9, another modification of the underlie is illustrated. In this form open coarse mesh metal fabric 11 of woven wire is thinly coated with rubber matrix 12 which spans across and closes the mesh. At the underside of the underlie the matrix is in the form of thin walled protuberances 13 which present downwardly exposed convex surfaces in the shape of spherical segments such as heretofore described. However, the upper surfaces of the protuberances are concave. Thus the upper surface of the underlie has a multitude of regularly distributed depressions between the strands as well as slight peaks at the intersections of the strands. This irregularity in surface contour provides an effective surface for engagement with the rug to constrain it from movement relative to the underlie. As in the other forms, the bases of the protuberances 13 in the plane of the fabric are confined against lateral expansion and movement and since the depending portions of the protuberances are thin walled and flatten readily under pressure, a large area of each is exposed to and engages the floor without transmitting increments of movement to adjacent protuberances. This form of underlie can be made very readily by coating the metal fabric with very stretchy and resilient rubber composition which is more flowable than that heretofore described. Preferably the rubber or composition is rendered flowable by means of a volatile solvent. After coating the fabric with a layer of the desired thickness the coated fabric is supported in horizontal position and a moderate air stream is blown against the upper surface, the force of the air stream depending somewhat upon the fluidity or flowability of the matrix. The force of the air stream is maintained against the coated fabric until the protuberances 13 are formed and may be maintained, though usually with lessened force, until the material has set by evaporation of the solvent. Since the upper surface of this form of the underlie contains many crests and depressions, the crests and depressions provide an anchor means for the rug and the addition of the coarse irregular particles on the upper surface is unnecessary.

It is to be noted that in all of the figures the thickness of the material has had to be exaggerated for clearness in showing sections and the like and that, therefore, the drawings without explanation may give a distorted picture of the proportions of the underlie.

In Fig. 9, however, the proportions are suitable, assuming the mesh is about one-half inch.

Considerable variation may be made in the underlie but the protuberances should be large in horizontal projection relative to their height in any case. The mesh may be square, rectangular or in other shapes. As a suitable example, an underlie employing a fabric with a square mesh of from one-half to one and one-half inches may have protuberances of about one-eighth to three-eights inches high. In the form illustrated in Figs. 7 through 9 the overall thickness of the underlie using a mesh having woven wire strands of about one-thirty second inch diameter and mesh one-half inch square is about one-quarter inch.

Referring next to Figs. 10 and 11, an underlie indicated generally at 14 using a coarse open mesh fabric of flat metal strands is illustrated. This underlie is the same as that heretofore described except for the type of strand shown and is particularly desirable where very limited height of the underlie is desired.

The form of underlie to be used in a given case is dictated largely by the desires of the user. For example, for relatively light weight or thin rugs considerable padding is usually desired between the rug and floor in which case the thick underlie of Figs. 1 through 4 may be used. For rugs of moderate weight the form illustrated in Figs. 5 and 6 usually is preferred to the thicker form of Figs. 1 through 4. For thick rugs when a minimum of padding is desired, the form illustrated in Figs. 7 through 9 or Figs. 10 and 11 may be used. If desired, the underlie may be secured to the rug at the margins in any suitable manner but such is not necessary.

Having thus described my invention, I claim:

1. A rug underlie comprising coarse mesh metal fabric which is relatively rigid in its plane and flexible flatwise, a coating of resilient soft rubber composition embedding the fabric and having, extending from one face of the fabric beyond the plane thereof, a multitude of integral convex protuberances, the protuberances being aligned with and spanning the meshes, respectively, and each protuberance having its base surrounded by, and constrained from elastic deformation in the plane of the fabric by, the portions of the strands of the fabric defining the mesh with which the protuberance is aligned.

2. A rug underlie in accordance with claim 1 characterized in that said protuberances and underlie as a whole are non-porous.

3. A rug underlie according to claim 1 characterized in that the over-all height of each protuberance normal to the plane of the fabric is greater than the thickness of the fabric.

4. An underlie for the purposes described, comprising coarse mesh metal fabric which is relatively rigid in its plane and flexible flatwise, coated with a relatively thin layer of soft resilient rubber composition which is permanently bonded thereto and spans across the meshes, the portions of the coating spanning across the meshes being, respectively, relatively thin-walled soft resilient protuberances, each of which is convex at one face of the underlie and extends outwardly beyond the plane of the fabric and is concave toward the opposite face of the underlie, the base portion of each of the protuberances lying substantially within the plane of the fabric and the protuberances lying substantially within the plane of the fabric and the protuberances being integrally bonded together and to the fabric at their bases.

FERD W. BINGELL.
